United States Patent Office.

CHARLES A. KING, OF SPRINGFIELD, MASSACHUSETTS.

Letters Patent No. 95,912, dated October 19, 1869.

IMPROVED LUBRICATOR FOR LOOSE PULLEYS.

The Schedule referred to in these Letters Patent and making part of the same.

To all whom it may concern:

Be it known that I, CHARLES A. KING, of Springfield, Hampden county, State of Massachusetts, have invented a new and useful improved Oiler for Loose Pulleys; and I do hereby declare that the following is full and clear description thereof, reference being had to the accompanying drawings, and to the letters of reference marked thereon.

In the drawings—

Figure 1 is a side view of a pulley with my improvements, showing the interior arrangements of the same;

Figure 2, a cross sectional view; and

Figure 3, a perspective view in detail.

The principle involved in this invention is that the lubrication of the loose pulley is accomplished by means of the centrifugal force obtained by the quick revolution of said pulley, this centrifugal force operating directly upon the valve communicating between the supply-chamber and the lubricator, opening the valve when the pulley is in quick motion. The valve is closed again by means of a spring or other suitable power, when the pulley has ceased to revolve, or the motion has decreased in rapidity so much that the centrifugal force is not sufficient to overcome this power continually bearing against the valve and tending to shut it.

In the drawings—

A is the supply-chamber, formed in the shape of a hollow ring, and slid over the hub of the pulley, resting against the spokes, and fastened to the hub by means of the lubricating tube B, which is screwed through the rear projecting portion of the chamber at C. The end of this tube being bevelled and fitting into a corresponding socket cut through the hub at this point, oil is delivered upon the shaft D through this tube.

The communicating duct between the supply-chamber A and the lubricator B consists of a small passage, E, cut through the back plate of the chamber, and leading into the tube itself, or space above it, as the case may be.

The valve consists of a piece, F, hinged to the back plate of the chamber at G, and having at its swinging end a block, H, which fits closely to the side of the chamber over the hole E. A spring, I, presses against the piece F and keeps it against a pin, J, which limits its play toward the shaft.

An adjustable screw, K, is set through the perime-

ter of the chamber, and regulates the play of the valve away from the centre.

A hole, L, is cut through the block H in the portion nearer the centre, and this hole comes opposite the hole E, communicating with the lubricator when the valve is pressed out against the screw K. But when the valve is at rest, as shown in figs. 1 and 2, the holes L and E do not communicate.

By setting the screw K in or out, the holes may be made to communicate more or less, so as to regulate the feed of the oil to the lubricator.

Fig. 1 represents the valve as thrown out against the screw K, the pulley being in rapid motion.

The passage of the oil from the chamber to the tube is much facilitated by the centrifugal force which compels its passage through the communicating ducts. This force also prevents the oil from feeding to the shaft to any extent while the pulley is in quick motion, and the passage free between the chamber and tube. But when the pulley is moving slowly, the tube is left nearly full of oil after the valve has closed, and this supply is constantly in direct contact with the shaft, oiling it after use, and remaining next to it when at rest.

A hole, O, is made through the front plate of the chamber for the purpose of filling it, and is stopped with a screw-cap.

The advantage of this invention is, that the pulley is always kept perfectly supplied with oil at a small expense of time and cost.

As various alterations may be made in my improvements without affecting the principle involved, I do not confine myself to the exact construction herein shown of the parts composing the device; but

What I claim as new, and desire to secure by Letters Patent, is—

1. A valve for pulley-lubricators, operated by the centrifugal force obtained from the revolution of the pulley, said valve opening and shutting a passage communicating with the pulley-bearing.

2. The combination of the supply-chamber A, oiling tube B, valve F, and spring I, the parts being constructed and arranged substantially as herein set forth.

3. The independent annular oil-chamber A, constructed in the manner and for the purpose set forth.
